WATER SPRINKLER

Homer M. Barnhart, Pomona, Calif.

Application April 21, 1931, Serial No. 531,789

27 Claims. (Cl. 299—68)

My invention relates to a water sprinkling device that is especially designed for use on lawns, golf courses, gardens, orchards or wherever a thorough distribution of water is desired over a 5 relatively large area and the principal objects of my invention are, to generally improve upon and simplify the construction of the existing forms of rotary water sprinklers and to provide a sprinkler of the rotary type that is relatively 10 simple in construction, inexpensive of manufacture and which will be very effective in performing the functions for which it is intended.

Further objects of my invention are, to provide 15 a water sprinkler, wherein the housing that carries the jet nozzle is caused to slowly rotate about its axis as a result of the impingement of a relatively small jet of water against a wheel having radially disposed blades and which wheel functions for the distribution of water throughout the 20 area immediately adjacent to the point where the sprinkler is positioned, further, to provide a sprinkler having a housing within which are formed separate chambers, one of which contains the vertical bearings for the housing and 25 also the gearing that is utilized for imparting rotary motion to said housing, the other chamber functioning as a water circulation chamber and having jet nozzles projecting therefrom and further, to provide simple and efficient means for 30 controlling the jet of water that impinges against the blades of the water spreading wheel and likewise for controlling the pressure and force of said jet of water.

Further objects of my invention are, to provide 35 a sprinkler of the character referred to having a separate water chamber that is connected to the source of supply and from which projects the main jet nozzle, to provide simple and efficient means within said water chamber for producing a perfect balance of the thrust resulting 40 from the pressure of the water passing through said chamber and further, to provide an improved construction wherein wear between moving parts of the rotating housing and the gearing container therein is minimized.

A further object of my invention is, to provide 45 improved packings for the bearings between the water housing and its support so as to practically eliminate the possibility of the development of wear in said bearings as a result of the presence of sand, grit and the like that passes through the sprinkler with the water that is delivered to and discharged therefrom.

A further object of my invention is, to provide 50 a rotary sprinkler having relatively simple and

efficient means whereby the necessary adjustments may be made so as to cause said sprinkler to operate at highest efficiency under all conditions of variable water pressure, speed of rotation of the nozzle carrying head and the variable 60 areas to be covered by the water that is discharged from the rotary head.

With the foregoing and other objects in view, my invention consists in certain novel features of construction and arrangement of parts that 65 will hereinafter be more fully described and claimed and illustrated in the accompanying drawings in which:

Fig. 1 is a side elevational view of a water 70 sprinkler constructed in accordance with my invention, and with the lower portion thereof shown in vertical section.

Fig. 2 is a detail section taken on the line 2—2 of Fig. 1.

Fig. 3 is a detail section taken on the line 3—3 75 of Fig. 1.

Fig. 4 is a vertical section taken through the center of the rotating housing of my improved sprinkler and which housing carries the main jet nozzle and the gearing that is effective in rotating said housing.

Fig. 5 is a horizontal section taken on the line 5—5 of Fig. 4.

Fig. 6 is an enlarged vertical section taken on the line 6—6 of Fig. 5.

Referring by numerals to the accompanying drawings which illustrate a practical embodiment of my invention, 10 designates a housing preferably cast from metal and which housing is mounted between the upper portions of a pair of runners 11 having upturned ends 12, thus enabling the base structure and the parts carried thereby to be readily drawn over the surface of the ground and consequently permitting the sprinkler to be readily shifted from one position to another.

Projecting from the upper portion of housing 10 is a connection 13 for a supply pipe or hose 14 and arranged in the lower portion of the side wall of housing 10 is a removable plug 15 which permits access to the interior of the housing in order that accumulations such as sand and silt may be removed therefrom.

The lower portion of the chamber 16 within the housing, functions as a settling basin for the accommodation of sand and silt that may enter 105 the housing through the supply line.

The lower portion of a tubular post or standard 17 projects through the top of housing 10 and extends downwardly through the chamber there-in and this post is secured to the housing by 110

means of a plug 18 that is screwed into the lower portion of said tubular post and the lower portion of which plug bears against the bottom wall of housing 10.

5 Suitable packing rings 19 are arranged between plug 18 and the bottom of housing 10 and likewise between the top of said housing and a shoulder that is formed on the tubular standard 17.

10 The wall of the tubular standard 17, within the chamber 16 in housing 10, is perforated as designated by 20, and surrounding this perforated portion of the standard and spaced apart therefrom is a concentrically arranged perforated strainer 21. This strainer is effective in preventing sand, silt and other foreign substances from 15 passing from the supply pipe upwardly through the tubular standard 17.

The upper portion of tubular standard 17 is provided with perforations 22 and formed integral 20 with and projecting upwardly from the tubular standard immediately above these perforations is a post 23.

25 Surrounding the upper perforated portion of the standard 17 is a housing 24 and projecting from the side thereof is a short inclined tube 25 carrying at its outer end a removable jet nozzle 26, which is designed to discharge the main jet of water from the sprinkler.

30 Screw-seated on the tubular standard 17, immediately below housing 24, is a ring 27 provided at its upper end with a flange 28 having an inclined upper surface and said ring 27 may be located in its adjusted position upon the threaded portion of standard 17 by means of a clamping screw 29 that passes through ears 30 that project outwardly from said ring and the latter being 35 split between said ears.

30 Screw-seated on the lower end of housing 24 is a ring 31 having a flange 32 that projects toward flange 28 and resting on top of flange 32 is the outer portion of a packing ring or washer 33 of leather, rubber or suitable composition and the inner portion of this packing ring rests on the inclined upper face of flange 28.

45 Seated within the lower portion of housing 24 is a retaining ring 34 that clamps the outer portion of packing ring 33 against flange 32.

50 Surrounding the tubular post 17 and bearing directly on top of the inner portion of packing ring 33 above flange 28 is a retaining ring 35 of metal and disposed on top thereof is a packing ring 36, preferably of felt which surrounds the tubular post 17 and which is retained in position by an overlying ring 37 of metal.

55 Bearing on top of the ring 37 is the lower end of an expansive coil spring 38 and which surrounds the perforated portion of post 17.

60 Screw-seated on the upper portion of tubular post 17, is a ring 39 which is held by a lock ring 40 and bearing against the underface of this ring 39, which is inclined, is the inner portion of a packing ring 41 of leather, rubber or suitable composition. The outer portion of this packing ring bears against an internal shoulder that is formed 65 on the wall of housing 24 and screw-seated within said housing and bearing against the outer portion of said packing ring is a clamping ring 42, preferably of metal.

70 Bearing against the underside of the inner portion of the packing ring 41 is a ring 43 of metal and positioned against the underside of this ring is a packing ring 44 of felt or analogous material that is enclosed and retained in position by ring 45.

75 The inner and outer edges of the retaining rings

35 and 43 are concentric with and spaced apart from tubular post 17 and the adjacent retaining rings 34 and 42, with the result that there is no contact of metal between the tubular post 17 and the metal rings that retain the packing rings 33 and 41 in proper position against the flanges 28 and 39.

80 The upper end of expansive spring 38 bears against the underside of the retaining ring 45.

85 As a result of the construction just described, the pressure of the water passing through the chamber within housing 24 is directed equally against the packing rings 33 and 41, with the result that fluid pressure tight joints are produced between both ends of housing 24 and the tubular post 17 and the pressure exerted by coil spring 38 is also effective in producing and maintaining these tight joints.

90 Secured in any suitable manner to the inner face of the side wall of housing 24 are one or more vertically disposed plates 46 that function as baffles to prevent the whirling of water during its passage through the chamber within said housing.

95 Detachably secured in any suitable manner on top of housing 24 is a gear housing 47, the bottom plate of which is spaced a short distance above the retaining ring 39 so that there is an open air space 48 between the top of housing 24 and the bottom of housing 47. This space 48 permits any water that would otherwise tend to accumulate on top of the flexible head of housing 24, to be thrown outwardly by centrifugal force away from the sprinkler during the rotation of said head and the parts carried thereby.

100 Formed integral with the bottom wall of housing 47 and disposed concentrically with respect to post 23, which projects upwardly into the chamber within said housing, is an annular wall 49.

105 Positioned on the lower portion of the post 23 is a bearing ring 50 against which engages the upturned inner edge of a packing ring 51 of leather or analogous material and which ring rests on the bottom plate of housing 47 within the space encompassed by wall 49. The upturned inner edge of this packing ring is caused to hug the bearing ring 50 by a split compression ring 52 that encircles said upturned inner edge.

110 Arranged within the wall 49 and resting on the outer portion of packing ring 51, is a spacing ring 53 and bearing on the top thereof is a channel shaped ring 54 that functions as a cup race for a series of ball bearings 55.

115 The inner edge of ring 54 is spaced a slight distance apart from post 23.

120 Screw-seated on the intermediate portion of post 23 is a cone bearing ring 56, the lower end of which engages the ball bearings 55 and extended diametrically through post 23 immediately above this bearing ring is a pin 57 that is retained in position by an encircling snap ring 58. Screw-seated on post 23 immediately above this snap ring is a lock nut 59.

125 The anti-friction bearing comprising the cup race 54, balls 55 and cone bearing ring 56 constitutes an anti-friction bearing which resists upward thrust of the rotary head or housing, which results from the upward pressure of an expansive coil spring that is disposed between the bearing 130 at the upper end of post 23 and the top plate of the housing and which spring is hereinafter more fully described.

135 Screw-seated in the upper end of wall 49 is the lower end of a collar 60 and positioned on a flange

therein is a packing ring 61, preferably of felt, which prevents dust and the like from passing downwardly into the chamber occupied by the anti-friction bearings 55. This packing ring 61 is 5 retained in position within the collar 60 in any suitable manner.

By screwing collar 60 downward, pressure is applied to parts 54, 53 and 51 to maintain a tight joint between the anti-friction bearing in the lower portion of the gear housing 47.

Secured in any suitable manner to the upper end of post 23, is a worm wheel 62, and the upper end of the hub thereof forms a cone for a series of anti-friction ball bearings 63.

15 The lower end of a bearing ring 64 engages the ball bearings 63 and this ring 64 is positioned within a ring flange 65 that depends from the removable top plate 66 of housing 47.

A pin 67 that passes through ring flange 65 and 20 through vertically disposed slots in the upper portion of the bearing ring 64 retains the latter in the lower portion of said ring flange and bearing on top of said bearing ring 64 is the lower end of an expansive coil spring 68. The upper end 25 of this spring bearing against a removable cap 69, that closes the upper end of the chamber within ring flange 65. As above set forth spring 68 tends to lift the gear housing so as to maintain a proper bearing between cup race 54, bearing members 55 and cone bearing 56 and to also maintain proper bearing between the upper end of standard 23, bearing members 63 and the bearing cone 64.

Thus by the use of the expansive spring 68, the rotary head or housing practically floats on its 35 bearings while the sprinkler is in operation.

Secured to the upper portion of housing 47 on opposite sides thereof are the lower ends of an inverted U-shaped handle 70, by means of which the sprinkler may be readily lifted and carried.

40 Journalized in suitable anti-friction bearings 71 that are arranged within caps 72 and the latter being removably seated in the side walls of housing 47, is a transversely disposed shaft 73 that is formed in two parts telescopically connected and 45 disposed between said parts is an expansion spring 74 that normally forces said parts away from each other so as to maintain the bearing cones on the ends thereof against the anti-friction members of the bearings 71.

50 Secured on this shaft 73 is a worm 75 that engages the teeth of worm wheel 62.

Secured on shaft 73 is a worm wheel 76 that engages a worm 77 and the latter being secured on a shaft 78 that is formed in two parts telescopically connected and the outer ends of said 55 parts bearing in suitable anti-friction bearings in the side walls of housing 47.

A spring 79 is arranged between the two parts of shaft 78 for maintaining the cone bearing on the ends thereof in yielding engagement with the anti-friction bearing at the ends of said shaft and this shaft 78 is arranged below and disposed substantially at right angles to shaft 73.

Secured on shaft 78 is a gear wheel 80 that 60 meshes with a pinion 81 and the latter being secured on a shaft 82 that is disposed slightly above and to one side of shaft 78 and above and at right angles to shaft 73.

Shaft 82 is formed in two parts that are normally forced apart by an expansion spring 83 in order to maintain the cone bearing rings 84 that is carried by said shaft in engagement with suitable anti-friction bearings 85 that are located in the side walls of housing 47. One end of shaft 75 82 extends through a gland or stuffing box 86 that

is located externally of the wall of housing 47 and formed on the intermediate portion of the housing of said gland or stuffing box is a circumferential flange 87 that functions to cause water to drip off the gland or stuffing box and not pass therethrough.

The two-part shafts 73 and 78 are arranged so that the thrust received by the worms carried by said shafts is against the fixed cones on said shafts while the slip cones on the opposite ends of said shafts are retained against their bearings by the expansive springs 74 and 79 and shaft 82 and its bearings are arranged so that the fixed cone 84 receives the outward thrust that is impressed on shaft 82 by the bladed wheel while the same is in motion and thus the slip cone 84 is relieved of the thrust forces.

All cones carried by the shafts 73, 78 and 82 are secured by pins to the parts of the shafts so that said cones and shafts rotate together.

Extending diametrically through shaft 82, just beyond the gland 86, is a pin 87^a and bearing thereagainst, is the central portion of a combined driving and water spreading wheel comprising a disc 88 that is provided on its inner focus adjacent to its outer edge with a series of blades or vanes 89 that receive a jet of water from a nozzle hereinafter more fully described and the impact or force of the water against these blades or vanes imparts rotary motion to the wheel and to the shaft 82, upon which it is mounted.

Formed integral with and projecting inwardly from the disc 88 of the bladed wheel, is a ring flange 88^a that encircles the gland 86 and the edge of said ring flange surrounds flange 87. This ring flange is effective in protecting the gland 86 against the inward passage of water and foreign substances carried thereby for while the wheel is in motion any water that may pass inwardly along the inner face thereof, will be thrown radially outward by centrifugal force as it passes unto the outward surface of said ring flange 88^a.

Projecting outwardly from the center of this wheel is a hub 90, in which is formed a diametrically arranged slot 91 and occupying said slot is a pin 92 that passes diametrically through shaft 82.

Positioned upon hub 90 is a cap 93, the flange of which overlies the ends of slot 91 to prevent the unseating of pin 92 and this cap is retained in position on the hub 90 and the end of shaft 82 by a nut 94 that is screw-seated on the threaded end of said shaft. By tightening nut 94 the central portion of the wheel is clamped against pin 87 and thus said wheel is very firmly secured to shaft 82 and at the same time it may be readily removed therefrom.

Seated in the side wall of housing 24 on the same side of the rotating head with the water compact and spreading wheel is the lower threaded end of an elbow fitting 95 and arranged between said fitting and the wall of the housing is a packing ring 96 against which bears a gland nut 97.

Screw-seated in the upper portion of this elbow fitting 95 is the lower portion of a vertically disposed tubular member 98 and arranged between the members 95 and 98 is a packing ring 99 against which bears a gland nut 100.

The upper end of tubular member 98 terminates in a horizontally disposed head 101 and positioned against the open end of said head 101 is the open lower end of a short tube 102. Removably seated in the opposite end of this short tube is a jet nozzle 102^a that is adapted to dis-

charge a jet of water against the blades 89 on disc 88.

A packing ring 103 is interposed between the contacting edges of the parts 101 and 102 and said parts are connected by a horizontally disposed pin or bolt 104 on one end of which is mounted a clamping nut 105, beneath which is disposed a suitable packing ring.

The construction just described enables the tube 102 and jet nozzle 102^a to be raised or lowered so as to regulate and control the point of impact between the jet of water that issues from said nozzle and the blades or vanes 89.

A further adjustment of the jet nozzle toward and away from the axis of the elbow fitting 95 is provided by screwing the lower portion of fitting 98 into or out of the upper portion of elbow fitting 95 and locking said member 98 after adjustment by tightening gland nut 100.

Screw-seated in the lower portion of the fitting 95 directly opposite the leg that is screw-seated in the wall of housing 24, is a tubular plug 106 closed at its inner end by a plate or disc 107 and located between this plug and the wall of fitting 95 is a packing ring 108 that is retained in position by a nut 109 that is screw-seated on the outer portion of said plug.

This plug functions as an adjustable pressure regulator to control the volume flow of water from housing 24 through the elbow fitting 95, tubular member 98, tube 102 and jet nozzle 102^a and said adjustable plug is locked after adjustment, by tightening nut 109.

Seated in the wall of fitting 95, just above the pressure regulating plug 106, is a removable plug 110, which when removed permits a pressure gauge to be inserted into fitting 95 to ascertain the pressure of the water passing therethrough and thus yielding the requirement for adjustment of plug 106.

In the operation of my improved sprinkler, water enters housing 10 through supply line 14 and after passing through strainer 21 and apertures 20, said water passes upward through tubular member 17 and out through apertures 22 to the chamber within housing 24.

From housing 24 water passes through upwardly inclined tubular member 25 and discharges through jet nozzle 26 and this jet of water is distributed throughout a wide radius, as the head or housing rotates on the upper portion of tubular standard 17.

The water passing through housing 10 is strained as it passes through the strainer 21 and all sand, silt and other foreign matter that cannot pass through this strainer, accumulates in the settling chamber 16 and may be removed from time to time by removing plug 15 that normally closes the cleanout opening.

The pressure of the water passing through the chamber in housing 24 is applied uniformly to the packing members that close the upper and lower ends of said chamber and this pressure is effective in forcing the flexible packing members 33 and 41 outwardly against the flanges 28 and 39 and during the rotation of the housing 24 these packing washers bear against the relatively fixed flanges so that there is no metal parts in contact with each other as the housing 24 rotates on the tubular standard 17.

The packing rings 36 and 44 being of felt or analogous material prevents sand, silt and other foreign substance from entering the bearing between housing 24 and the tubular standard 17 and therefore the packing rings 33 and 41 which

serve as bearing members are protected against comparatively rapid wear which would otherwise result if they were subjected to the action of sand, slit or the like.

Water from the chamber within housing 24 passes through elbow fitting 95, tubular member 98, tube 102 and jet nozzle 102^a and the jet of water that discharges from this nozzle, impinges against the blades or vanes 89 on the water spreading wheel, thereby imparting rotary motion to said wheel and its shaft 82 upon which said wheel is mounted.

The blades or vanes 89 are shaped so that they will deflect and throw the water that strikes against them, outwardly for a considerable area immediately adjacent to the sprinkler and which area is not covered by the water that discharges from jet nozzle 26. As a result of this arrangement the entire area of the ground surface immediately adjacent to the sprinkler receives water from said sprinkler while the same is in operation.

As heretofore stated, the volume flow and pressure of water through elbow fitting 95, tubular member 98 and jet nozzle 102^a may be accurately controlled and regulated by proper manipulation of plug 106 and the degree of pressure discharging through this jet nozzle may be readily ascertained by connecting a suitable pressure gauge to the opening that is normally closed by plug 110.

After shaft 82 is rotated as a result of the impingement of the jet of water from nozzle 102^a against vanes or blades 89, pinion 81, meshing with gear wheel 80, imparts rotary motion to shaft 78 and through worm 77 and worm wheel 76 this rotary motion is imparted to shaft 73.

Worm 75, carried by shaft 73, engages worm wheel 62, but is secured on the upper end of post 23 and as a result housing 47 and parts carried thereby is caused to rotate about the axis formed by post 23 and tubular standard 17 and during such rotation, said housing 47 is supported by the anti-friction bearings 55 and 63.

The pressure of the water within the chamber in housing 24 is equalized against the packing elements at both ends of said water chamber and the spring 68 that is interposed between the upper one of the anti-friction bearings in the gear chamber, tends to equalize the pressure upon said bearings with the result that the entire head or housing and parts carried thereby rotate freely upon the axis formed by the tubular standard 17 and post 23 and the only metal to metal contact between the fixed and rotating parts are the cone bearings, races and anti-friction members that function as anti-friction bearings between the housing and the axis thereof.

The chamber within housing 47 is filled, or partially filled with grease or a heavy liquid lubricant, thereby providing ample lubrication for all operating parts within said housing.

The felt packing ring 61 contained within the upper portion of member 60 prevents the dust and grit from passing downwardly into the chamber occupied by the anti-friction bearings 55 and the bearing parts that cooperate therewith.

Thus the head comprising the housing 24 and 27 (which are separated by an open air space) is rotated upon the tubular standard 17 and post 23 and the jet of water issuing from jet nozzle 26 and the water that discharges from jet nozzle 102^a (which is distributed by the bladed wheel), is distributed throughout an area of considerable radius with the sprinkler as a center.

In assembling and adjusting the rotary head 150

for operation, the bearing ring 56 is screwed downward into annular wall 49 until balls 55 are engaged and when such engagement takes place, the entire head or housing is lowered to a slight degree so as to properly adjust the packing ring 41 so that the inwardly projecting portion thereof lies smooth and flat against the underside of ring 39.

This lowering of the housing also properly adjusts the inwardly projecting portion of packing ring 33 so that it lies smooth and flat upon flange 28. The parts 28, 32, 39 and the flange against which the outer edge of packing ring 41 engages are constructed so that when their outer faces align with each other or occupy the same horizontal planes, the packing rings 41 and 33 are properly positioned so as to operate at highest efficiency and produce the desired watertight joints at the ends of the water chamber within housing 24.

Thus it will be seen that I have provided a rotary sprinkler having a rotary head within which are formed separate water and gear chambers, with a main jet nozzle projecting from the water chamber and with the gear chamber containing the necessary gearing for imparting rotary motion to the head.

The rotary head is mounted on a post or standard so as to rotate thereon with minimum friction and there is no metal contact in the bearings between the water chamber and the support upon which the housing rotates.

The flexible packings at both ends of the water chamber are acted upon by the pressure of the water passing through said chamber and the entire bearing of the rotary head upon the standard is carried by anti-friction bearings that are disposed within the gear housing and which latter is filled with heavy oil or grease to facilitate the operation of the gears and operating parts within the gear compartment.

The water chamber and gear chamber, although connected to each other are separated by an open air space and the joints between the post or standard and the water and gear housings are packed so as to effectually prevent water from entering the gear chamber and likewise for preventing grease or oil from entering the water chamber.

When the sprinkler is not in use, the flexible packing elements at the ends of the water chamber are firmly held in place and in proper position by spring pressure and thus said parts are retained in position so as to function properly when the sprinkler is subsequently operated.

A further feature of my invention is, the provision of relatively simple and effective means for regulating the pressure of the water that discharges in jet form unto the bladed wheel and the means for regulating this pressure is located in the elbow fitting that leads from the water chamber so that said pressure regulation is entirely independent of the pressure of the water that discharges through the main nozzle 26.

A further feature of my invention is, the wide range of adjustability of the jet nozzle that directs a jet of water against the bladed wheel and likewise the adjustability of the parts that connect said jet nozzle with the water chamber of the sprinkler.

As a result of the equalization of the pressure of the water passing through the water chamber 24, all upward thrust which would otherwise be directed against the rotary head, is eliminated and said head while in operation practically

floats on its bearings with a minimum of friction and very little if any wear.

It will be understood that minor changes in the size, form and construction of the various parts of my improved water sprinkler may be made and substituted for those herein shown and described without departing from the spirit of my invention, the scope of which is set forth in the appended claims.

I claim as my invention:

1. In a water sprinkler, a base, a housing carried by said base, a water supply pipe connected to said housing, a tubular standard seated in said housing and projecting upwardly therefrom, a head mounted for rotation on the upper portion of said standard, a spring arranged between said standard and head for yieldingly supporting the latter, said head being provided in its lower portion with a chamber that has communication with the chamber in the tubular standard, a jet nozzle projecting from the chamber in the lower portion of said head and means carried by said head and actuated by the water passing therethrough for imparting rotary movement to said head.

2. In a water sprinkler, a base, a housing carried by said base, a water supply pipe connected to said housing, a tubular standard seated in said housing and projecting upwardly therefrom, a head mounted for rotation on said tubular standard, said head being provided with separate water and gear chambers, a spring arranged between said standard and head for yieldingly supporting the latter, there being a water drainage opening formed through said head between the water and gear chambers therein, a jet nozzle projecting from the water chamber, flexible packing elements arranged between the ends of the water chamber and said tubular standard, a second jet nozzle projecting from the water chamber, gearing arranged within the gear chamber for causing the head to rotate upon the tubular standard and a bladed wheel associated with said gearing and adapted to be rotated by the jet of water issuing from the second mentioned jet nozzle.

3. In a water sprinkler, a standard, a head mounted for rotation upon said standard, said head having separate water and gear chambers, a spring arranged between said standard and head for yieldingly supporting the latter, there being a water drainage opening formed through said head between said water and gear chambers, flexible packings arranged between the ends of the water chamber and said standard, a jet nozzle projecting from the water chamber, anti-friction bearings arranged within the gear chamber between the head and standard, driving gear connections between said head and standard, a bladed wheel connected to said driving gear connections and an adjustable jet nozzle projecting from the water housing and adapted to direct a jet of water against the blades of said wheel.

4. In a water sprinkler, a standard, a head mounted for rotation upon said standard, said head having separate water and gear chambers, flexible packings arranged between the ends of the water chamber and said standard, a spring arranged between said standard and head for yieldingly supporting the latter, a jet nozzle projecting from the water chamber, anti-friction bearings arranged within the gear chamber between the head and standard, driving gear connections between said head and standard, a

- bladed wheel connected to said driving gear connections, an adjustable jet nozzle projecting from the water housing and adapted to direct a jet of water against the blades of said wheel and means 5 for regulating the pressure of the water that passes through said last mentioned jet nozzle. 80
5. In a water sprinkler, a base, a housing supported by said base, which housing is provided in its upper portion with a water inlet opening, 10 said housing being provided in the lower portion of its wall with a normally closed cleanout opening, a tubular standard seated in and projecting upwardly from said housing, a head mounted for rotation on the upper portion of said standard, 15 said head having separate water and gear chambers, a spring arranged between said standard and said head for yieldingly supporting the latter, said head having a water drainage opening formed between said water and gear chambers, 20 a jet nozzle projecting from said water compartment, driving gear connections within said gear chamber between said head and the upper portion of said standard, a bladed wheel connected to said driving gear connections and a jet nozzle projecting from said water chamber for directing 25 a jet of water against the blades of said wheel. 95
6. In a water sprinkler, a standard, a head mounted for rotation on said standard, said head having separate water and gear chambers, anti-friction bearings located within the gear chamber 30 between said head and said standard, an expansive coil spring located between the upper one of said anti-friction bearings and the upper portion of said head, driving gearing located within the gear chamber between said head and standard, a bladed wheel carried by said head and connected to said driving gearing, an adjustable jet nozzle projecting from the water chamber for directing 35 a jet of water against said bladed wheel, a second jet nozzle projecting from said water chamber, flexible packing elements arranged between the ends of the water chamber and said standard and an expansive coil spring interposed between said packing elements. 100
- 40
7. In a water sprinkler, a standard, a head mounted for rotation on said standard, said head having separate water and gear chambers, anti-friction bearings located within the gear chamber 45 between said head and said standard, an expansive coil spring located between the upper one of said anti-friction bearings and the upper portion of said head, driving gearing located within the gear chamber between said head and standard, a bladed wheel carried by said head and connected to said driving gearing, an adjustable jet nozzle projecting from the water chamber for directing 50 a jet of water against said bladed wheel, means seated in said jet nozzle for regulating the pressure of the water passing therethrough, a second jet nozzle projecting from said water chamber, flexible packing elements arranged between the ends of the water chamber and said standard, an expansive coil spring interposed between said packing elements and means located 55 on the interior of the water chamber for preventing whirling of the water that passes therethrough. 105
- 60
8. In a water sprinkler, a standard, a head mounted for rotation on said standard, said head having a water chamber and a gear chamber, means for supplying water to said water chamber, jet nozzles projecting from said water chamber, a shaft journaled in said gear chamber, a bladed wheel carried by said shaft, which wheel 65 is driven by the jet of water issuing from one 110
- of said nozzles, gearing arranged within the gear chamber between said standard and the shaft that carries the bladed wheel, anti-friction bearings within said gear chamber between said head and standard, an expansion spring arranged between the upper one of the friction bearings and the upper portion of said head and packing glands within said water chamber between said head and said standard and means for yieldingly maintaining said packing glands in close engagement with said standard. 115
9. In a water sprinkler, a standard, a head mounted for rotation on said standard, said head having a water chamber and a gear chamber, means for admitting water to said water chamber, jet nozzles projecting from said water chamber, a shaft journaled in said gear chamber, a bladed wheel carried by said shaft, which wheel is driven by the jet of water issuing from one of said nozzles, gearing arranged within the gear chamber between said standard and the shaft that carries the bladed wheel, anti-friction bearings within said gear chamber between said head and standard, an expansion spring arranged between the upper one of the anti-friction bearings and the upper portion of said head for counter-balancing the weight of said head and for exerting yielding pressure on both sets of said anti-friction bearings and spring pressed packing glands within said water chamber between said head and said standard. 120
10. In a water sprinkler, a standard, a head mounted for rotation on said standard, said head having a water chamber and a gear chamber, anti-friction bearings within said gear chamber between said head and standard, an expansion spring arranged between the upper one of the anti-friction bearings and the upper portion of said head, packing glands within said gear chamber between said head and said standard, a jet nozzle projecting from said water chamber and means including gearing within the gear chamber, a bladed wheel connected to said gearing and an adjustable jet nozzle that projects from the water chamber and which is adapted to direct 125 a jet of water against said bladed wheel for imparting rotary motion to said head. 130
11. In a water sprinkler, a standard, a head mounted for rotation on said standard and having separate water and gear chambers, there being a water drainage space being formed between said water and gear chambers, a driving gearing arranged within the gear chamber between said head and standard, a bladed wheel connected to a part of said gearing, a longitudinally adjustable tubular member having one end 135 adjustably seated in the wall of the water chamber of the head and a jet nozzle adjustably mounted on said tubular member. 140
12. In a water sprinkler, a standard, a head mounted for rotation on said standard and having a water chamber and a gear chamber, driving gearing arranged within the gear chamber between said head and standard, a bladed wheel connected to a part of said gearing, a longitudinally adjustable tubular member having one end adjustably seated in the wall of the water chamber of the head, a jet nozzle adjustably mounted on said tubular member and adapted to direct a jet of water onto the blades of said 145 bladed wheel and means located in said tubular member for regulating the pressure of the water passing therethrough. 150
13. In a water sprinkler, a standard, a head mounted for rotation on said standard and hav-

- ing a water chamber, a jet nozzle projecting from said water chamber, a shaft journaled in said head, a bladed wheel carried by said shaft for receiving the jet of water issuing from said jet nozzle, driving gear arranged between said standard and shaft, flexible rings having their outer portions detachably secured to the ends of the water chamber, shoulders on the standard, which shoulders bear against the external faces 5 of the inner portions of said flexible rings, bearing rings engaging against the inner faces of the inner portions of said flexible rings, packing rings encircling the standard and engaging said bearing rings, retaining rings enclosing said pack- 10 ing rings and engaging said bearing rings, an expansive coil spring interposed between said retaining rings and an expansive spring arranged between a bearing element on said standard and the head. 15
- 20 14. In a water sprinkler, a rotatably mounted head having separate water and gear chambers, said water and gear chambers being spaced apart so as to form between them a water drainage space, a main jet nozzle projecting from the water chamber, driving gearing arranged within said gear chamber, a bladed wheel arranged on the exterior of said head and connected to said gearing and an adjustable nozzle projecting from the water chamber for directing a jet of water against the blades of said wheel. 25
- 30 15. In a water sprinkler, a rotatably mounted head having separate water and gear chambers, a main jet nozzle projecting from the water chamber, driving gearing arranged within said gear chamber, a bladed wheel arranged on the exterior of said head and connected to said gearing, an adjustable nozzle projecting from the water chamber for directing a jet of water against the blades of said wheel and means seated in said adjustable jet nozzle for regulating the pressure of the water passing therethrough. 35
- 40 16. In a water sprinkler, a rotatably mounted head having separate water and gear chambers, a main jet nozzle projecting from the water chamber, driving gearing arranged within said gear chamber, a bladed wheel arranged on the exterior of said head and connected to said gearing, an adjustable nozzle projecting from the water chamber for directing a jet of water against the blades of said wheel, means seated in said adjustable jet nozzle for regulating the pressure of the water passing therethrough, a tubular standard on which the head is mounted for rotation, a chamber within the standard having communication with the water chamber, a spring arranged between said standard and said head for yieldingly supporting the latter and a base supporting said standard. 50
- 55 17. In a water sprinkler, a standard, a housing mounted for rotation on said standard, said housing having separate water and gear chambers, a plurality of shafts journaled for rotation within said gear chamber, conjoined worms and worm wheels arranged between said standard and shafts, a bladed wheel carried by one of said shafts outside the housing, a jet nozzle projecting from said housing for directing a jet of water unto said bladed wheel, each shaft being formed in two parts, cone bearings carried by the parts of each shaft and a spring arranged between the parts of each shaft. 60
- 65 18. In a water sprinkler, a journaled shaft, a bladed wheel removably positioned on said shaft, means on said shaft against which said wheel bears to limit the movement of said wheel in one 70 direction, a slotted hub on said wheel, a pin passing through the shaft and seated in the slot in said hub, a cap overlying said hub and the pin seated therein, a nut screw-seated on the shaft and bearing against said cap and a jet nozzle arranged to direct a jet of water against said bladed wheel for rotating the same and said shaft. 75
- 80 19. In a water sprinkler, a rotary head, a shaft, bearings in said head for said shaft, a gland for one of said bearings, a bladed wheel carried by said shaft, a jet nozzle projecting from said rotary head for directing a jet of water against said bladed wheel to rotate the same and said shaft and a water discharging ring flange on said bladed wheel, which flange encloses said gland. 85
- 90 20. In a water sprinkler, a standard, a housing journaled for rotation on said standard, said housing having separate water and gear chambers, there being a water drainage space formed between said chambers, anti-friction bearings between said housing and standard, a worm wheel fixed on said standard within said housing, a shaft journaled within the housing, a worm carried by said shaft and engaging said fixed worm wheel, a second worm wheel carried by said shaft, a second shaft journaled in bearings within the housing below and at right angles to said first mentioned shaft, a worm carried by said second mentioned shaft with which the second worm wheel on the first mentioned shaft engages, 100 a gear wheel carried by said second mentioned shaft, a third shaft journaled in said housing above and at right angles to the first mentioned shaft, a pinion secured to said third mentioned shaft, which pinion engages the gear wheel on the second mentioned shaft a bladed wheel mounted on said third mentioned shaft outside said housing and a jet nozzle arranged to direct a jet of water against said bladed wheel and communicating with said water chamber. 105
- 110 21. In a water sprinkler, a standard, a housing journaled for rotation on said standard, said housing having separate water and gear chambers, there being a water drainage space formed between said chambers, anti-friction bearings between said housing and standard, a worm wheel fixed on said standard within said housing, a shaft journaled within the housing, a worm carried by said shaft and engaging said fixed worm wheel, a second worm wheel carried by said shaft, a second shaft journaled in bearings within the housing below and at right angles to said first mentioned shaft, a worm carried by said second mentioned shaft with which the second worm wheel on the first mentioned shaft engages, 115 a gear wheel carried by said second mentioned shaft, a third shaft journaled in said housing above and at right angles to the first mentioned shaft, a pinion secured to said third mentioned shaft, which pinion engages the gear wheel on the second mentioned shaft, a bladed wheel mounted on said third mentioned shaft outside said housing, a water chamber within the lower portion of said housing, a main jet nozzle projecting upon said water chamber and a secondary jet nozzle projecting from said housing and adapted to direct a jet of water against the blades of said wheel. 120
- 125 22. In a water sprinkler, a standard, a housing mounted for rotation on the upper portion of said standard, means including gearing, a bladed wheel and a jet nozzle carried by said housing for causing rotation thereof on the standard, antifriction bearings arranged between said housing and standard, a cone bearing ring adjustably 130
- 135 140
- 145 150

mounted on said standard and engaging one of the antifriction bearings and an expansive spring arranged between the other antifriction bearing and the upper portion of said housing for counteracting the weight of the housing on the standard and for taking up wear and lost motion in said antifriction bearings.

23. In a water sprinkler, a tubular standard, a housing mounted for rotation upon said standard, means including gearing, a bladed wheel and a jet nozzle carried by said housing for causing rotation of said housing upon the standard, said housing having a water chamber from which said nozzle projects and which water chamber is in communication with a duct through said tubular standard, oppositely arranged flexible seals between the ends of said water chamber and said tubular standard, said seals being disposed on opposite sides of the point of communication between the duct through the tubular standard and the water chamber and an expansive spring disposed between said flexible seals.

24. In a water sprinkler, a tubular standard, a housing mounted for rotation on said standard, said housing having separate gear and water chambers, a water drainage space formed through the housing between said water and gear chambers, a nozzle projecting from the water chamber, a second nozzle projecting from said water chamber, a bladed wheel mounted for rotation on the housing with its blades in the path of travel of the jet of water that issues from said second mentioned nozzle and gear connections between said bladed wheel and said standard, which gear connections are located within the gear chamber of said housing.

25. In a water sprinkler, a standard, a housing mounted for rotation on said standard, a shaft journaled in bearings on said housing one of which bearings is provided with a grease chamber, gear connections between said shaft and said standard, a bladed wheel carried by the outer end of said shaft, a flange carried by said bladed wheel and surrounding the shaft bearing that is provided with the grease chamber and a jet nozzle carried by said housing for directing a jet of water against the blades of said wheel.

26. In a water sprinkler, a standard having an axial duct, a housing mounted for rotation on said standard, which housing is provided with

separate water and gear chambers a plurality of antifriction bearings between said housing and standard, an expansive spring arranged between said standard and housing for counterbalancing the weight of said housing and for taking up wear and lost motion in said antifriction bearings, the water chamber being disposed about that portion of the chamber having the axial duct, the wall of the standard around the duct being provided with ports that communicate with the water chamber, the external diameter of that portion of the standard that passes through the water chamber being uniform, flexible seals arranged between the ends of the water chamber and the standard above and below the ports in said standard, a shaft journaled in that portion of the housing having the gear chamber, a bladed wheel carried by said shaft, driving gear between said shaft and standard and a jet nozzle projecting from the water chamber of the housing for directing a jet of water against the blades of the wheel.

27. In a water sprinkler, a standard having an axial duct, a housing mounted for rotation on said standard, which housing is provided with separate water and gear chambers, the water chamber being disposed about that portion of the chamber having the axial duct, the wall of the standard around the duct being provided with ports that communicate with the water chamber, the external diameter of that portion of the standard that passes through the water chamber being uniform, flexible seals arranged between the ends of the water chamber and the standard above and below the ports in said standard, a shaft journaled in that portion of the housing having the gear chamber, a bladed wheel carried by said shaft, driving gear between said shaft and standard, a jet nozzle projecting from the water chamber of the housing for directing a jet of water against the blades of the wheel, anti-friction bearings arranged between the upper and lower portions of the gear chamber and said standard and a spring interposed between the upper one of said anti-friction bearings and the upper portion of the housing for counterbalancing the weight of said housing and for taking up wear and lost motion in said antifriction bearings.
